**FLOOR CLEAN-UP MECHANISM FOR
CONTINUOUS MINER**

Charles W. Fitzgerald, Franklin, Pa., assignor to Joy Manufacturing Company, Pittsburgh, Pa., a corporation of Pennsylvania

Application November 25, 1955, Serial No. 548,882

16 Claims. (Cl. 198—9)

This invention relates to floor clean-up mechanisms and more particularly to a floor clean-up mechanism especially designed for use with a continuous mining machine for cleaning up any loose mineral which may fall to the floor during the mining operation.

In a continuous mining machine of the type known as a "Joy continuous miner," a mobile base carries a disintegrating head mechanism for tearing mineral from a solid mine vein and conveying means on the base receives the disintegrated mineral discharged from the head mechanism and conveys it rearwardly of the machine to a convenient point of discharge. During the disintegrating operation some of the loose mineral may fall to the mine floor and must be cleaned up for efficient operation of the machine. Various known forms of clean-up mechanisms have been devised for association with the disintegrating head mechanism of a continuous miner for cleaning up the mine floor and the present invention contemplates improvements over such known types of clean-up mechanisms.

An object of the present invention is to provide an improved floor clean-up mechanism. Another object is to provide an improved floor clean-up mechanism especially designed for use with a continuous mining machine for cleaning up the mine floor during the mining operation. A further object is to provide improved means for mounting the clean-up scrolls on the machine and for driving the scrolls. A still further object is to provide improved stop means for limiting swinging movement of the conveyor scroll housings in vertical planes. Still another object is to provide improved pivotal mounting means for the conveyor scrolls for confining swinging motion of the scrolls to vertical planes extending transversely of the machine with the scrolls swinging about parallel horizontal axes extending longitudinally of the machine. Another object is to provide improved tilting means for the conveyor scrolls which are coordinated with the tilting means for the front end of the conveyor. These and other objects and advantages of the invention will, however, hereinafter more fully appear in the course of the ensuing description.

In the accompanying drawings there is shown for purposes of illustration one form which the invention may assume in practice.

In these drawings:

Fig. 1 is a fragmentary plan view and Fig. 2 is a fragmentary side view of a continuous mining machine incorporating an illustrative form of the improved floor clean-up mechanism.

Fig. 3 is a central longitudinal vertical section taken on line 3—3 of Fig. 1, with parts shown in full to facilitate illustration.

Fig. 4 is a section taken on line 4—4 of Fig. 3, looking down toward the conveying means and the clean-up mechanism.

Fig. 5 is an enlarged horizontal section taken on line

5—5 of Fig. 2, showing details of the clean-up mechanism.

Fig. 6 is a transverse vertical detail section taken on line 6—6 of Fig. 5, showing a scroll housing projection.

Fig. 7 is a transverse section taken on line 7—7 of Fig. 5, showing a scroll housing and conveyor scroll.

Figs. 8 and 9 are fragmentary side views, partially in section, showing the scroll housings in different tilted positions.

Fig. 10 is an enlarged detail horizontal section taken on line 10—10 of Fig. 8, showing details of the stop means for the scroll housings.

Fig. 11 is a diagrammatic view showing the hydraulic fluid system.

The continuous mining machine or so-called "Joy continuous miner" is generally designated 1 and an improved floor clean-up mechanism, generally designated 2, is operatively associated therewith for cleaning up any loose mineral which has fallen to the mine floor during the mining operation. The mining machine may assume various forms but herein may desirably be of the same general character as that disclosed in the John D. Russell application Serial No. 102,995, filed July 5, 1949, now matured into Patent No. 2,798,714, dated July 9, 1957, owned by the assignee of the present invention.

The continuous mining machine 1 generally comprises a mobile base 3 having a frame 4 on which is pivotally mounted at 5 a disintegrating head mechanism 6. This disintegrating head mechanism comprises a swingable frame 7 about which a series of parallel endless disintegrating chains 8 are guided for circulation in vertical orbits and at the outer portion of the head frame at the outer sides of the parallel chains and disposed in parallelism therewith are disintegrating wheels 9 which cooperate with the chains in the disintegration of the mineral.

Extensible fluid jacks or fluid cylinder devices 10 mounted at the sides of the head frame 7 are operatively connected through levers 11 and chain-links 12 for swinging the head mechanism 6 upwardly in vertical planes about its pivot. Carried by the base frame is conventional conveying means 14 having a central endless drive chain 15 to which conveyor flights 16 are attached at spaced intervals and the forward receiving portion of the conveying means extends forwardly and downwardly beneath the head pivot, as shown in Fig. 3. The endless drive chain 15 of the conveying means at the forward portion of the latter passes around a sprocket 17 secured to a transverse horizontal foot shaft 18 which is journaled at the sides of the forward portion of a tiltable front portion 19 of a conveyor frame 20. The pivot for the tiltable forward portion of the conveyor frame is designated 21 (Fig. 3). Extensible fluid jacks or fluid motor cylinder devices 22 serve to tilt the frame portion 19 about its pivot to raise and maintain the forward portion of the conveying means above the floor level.

The forward portion of the tiltable conveyor frame 20 has a floor engaging shoe 23 disposed transversely beneath the foot shaft and this shoe may rest upon the mine floor during operation of the clean-up mechanism.

The floor clean-up mechanism 2 may be generally similar to that disclosed in a copending application to John D. Russell Serial No. 141,137, filed January 28, 1950, now matured into Patent No. 2,744,607, granted May 8, 1956, of common ownership, and is adapted to gather loose mineral on the mine floor and to move a portion of the mineral inwardly toward the front receiving portion of the conveying means and to pile up a substantial portion of mineral beneath the disintegrating head. The disintegrating chains of the head, when the latter is swung downwardly into its lowered position, may

engage the piled up mineral and move it forwardly, upwardly and then rearwardly for discharge onto the conveying means rearwardly of the front receiving portion of the latter, in the manner fully disclosed in the above mentioned application Serial No. 102,995, now Patent No. 2,798,714.

The floor-clean-up mechanism, in this illustrative construction, includes lateral brackets in the form of gear housings 25 rigidly attached to the vertical side plates 26 of the conveyor frame and rigidly held in position as by bolts and screws. The foot shaft 18 is suitably rotatably supported at its ends by bearings carried within the gear housings, as later described. The brackets or gear housings have lateral luglike projections 27 and 28 and supported within the projections 27 are pivot pins 29. These pivot pins carry bearing sleeves 30 which are fitted within openings 31 in spaced lugs 32 integral with a bracket 33 rigidly secured to scroll housings 34. The luglike projections 28 are spaced apart and have aligned openings 35 in which a pivot pin 36 is fitted and the bracket 33 has a projecting lug 37 disposed between the spaced lugs 28 and pivotally engaging the pivot pin 36. The pins 29 and 36 are disposed in axial alignment and extend horizontally longitudinally of the machine. The pivot pins provide pivotal mountings for the scroll housings for confining the latter to tilting movement in vertical planes extending transversely of the machine.

Journaled within the scroll housings are rotatable conveyor scrolls 38 having tubular bodies 39 to which spiral flights or vanes 40 are secured as by welding. The scroll axes extend forwardly and inwardly at the sides of the conveying means as shown in Fig. 4 and the scrolls have free inner ends. The scroll bodies are suitably secured to a shaft 41 keyed at 42 to a sleeve-like shaft 43 suitably journaled within gear housings 44 providing the outer portions of the scroll housings.

The chain 15 of the conveying means effects drive of the foot shaft 18 (Fig. 5) and this foot shaft is coupled at its ends at 45 to and is supported by aligned shafts 46 suitably journaled within the gear housings 25. Integral with the shafts 46 and arranged within the gear housings are spur gears 47 meshing with spur gears 48 secured to tubular shafts 49 likewise suitably journaled within bearings supported within the gear housings 25. Keyed at 50 within the tubular shafts 49 are elements of conventional universal joints 51. Shafts 52 are splined at their inner ends at 53 to the inner elements of the universal joints and at their outer ends at 54 to the inner elements of conventional universal joints 55. The outer elements of the universal joints 55 are keyed at 56 to shafts 57 arranged in parallelism with the shafts 41 and likewise suitably journaled within the gear housings 44. Gears 58 journaled on the shafts 57 are connected by toothed "chatter" clutches 59 to the shafts 57 and these clutches are loaded by springs 60 which may yield upon overload to permit the clutches to slip. The gears 58 mesh with intermediate gears 61 which in turn mesh with and drive spur gears 62 formed integral with the shafts 43. Thus through the splined shafts and universal joints the conveyor scrolls may be driven irrespective of the tilted positions thereof about the axes of the pivot pins 29 and 36.

The scroll housings have longitudinal chambers 64 provided with curved inner surfaces and in which the conveyor scrolls are arranged with the inner ends of the scrolls projecting freely outwardly beyond the open inner ends of the chambers, as shown in Fig. 5, and the housings have downwardly extending front lip portions 65 (Fig. 7) for directing loose mineral rearwardly and upwardly toward the housing chambers as the clean-up mechanism is advanced over the mine floor. Bottom extensions 66 project longitudinally from the scroll housings beneath the free inner ends of the conveyor scrolls for directing the disintegrated mineral discharged from the scrolls inwardly toward the front receiving portion of the conveying means with some of the mineral piling

up on the mine floor in advance of the floor engaging shoe 23 of the conveyor frame.

Extending transversely from the sides of the parallel vertical side plates 26 of the conveyor frame, with their axes lying in a common transverse vertical plane, are extensible power jacks or fluid motors 67 comprising fluid cylinders 68 containing reciprocable pistons 69 having their piston rods 70 pivotally connected at 71 to pivot pins supported by lateral lugs projecting outwardly from the frame plates 26 (Figs. 8, 9 and 10) to the cylinders 68 which are pivotally connected at 72 to pivot pins supported by vertical lugs integral with the scroll housings. Thus when fluid under pressure is properly supplied to the jack cylinders the conveyor scrolls may be swung in vertical planes about their pivots and by trapping fluid in the jack cylinders the conveyor scrolls may be held in elevated position. Conversely when the front conveyor frame portion is swung downwardly the scroll housings swing downwardly about their pivots. During the floor clean-up operation the fluid in the jack cylinders may be vented so that the scroll housings may ride freely over the mine floor with the scroll housings moving up and down about their pivots as they slide over an uneven floor or rolling bottom.

In this improved construction, stop means are provided for limiting the opposite vertical swinging movements of the scroll housings and one of these stop means comprises a pair of parallel links 74 pivotally engaging a horizontal pivot pin 75 supported by lateral lug 76 secured to the housings 25. The opposite ends of the links carry parallel pins 77 engaged in longitudinal slots 78 in vertical plates 79 secured to the scroll housings (Fig. 10). The axes of the pins 75 and 77 are disposed in parallelism with the axes of the pivot pins 29 and 36 for the scroll housings, and the links may swing in vertical planes parallel to the vertical plane which includes the longitudinal axes of the power jacks 67, as shown in Figs. 4 and 10. Thus as the scroll housings swing downwardly in vertical planes about their pivots the ends of the slots 78 engaging the pins 77 limit the swinging movement of the scroll housings in the downward direction. The other stop means for limiting upward swing of the scroll housings comprises abutment surfaces 80 on the plates 79 engaging abutment surfaces 80' on the lugs 76. As the scroll housings ride over an uneven floor the slotted links permit the scroll housings to swing freely up and down within normal limits, thereby to enable the scroll housings readily to follow the contour of the floor.

Now referring to the improved hydraulic fluid system operatively associated with the several jack cylinders, it will be noted that a conventional motor driven pump 81 (Fig. 11) has its intake side connected by a conduit 82 to a fluid tank or reservoir 83 and the discharge side of the pump is connected by a conduit 84 to the pressure passage of the valve box of a conventional control valve mechanism 85. The return passage of the valve box is connected by a conduit 86 back to the tank. The valve box has usual parallel bores which receive slide valves 87 and 88 of the conventional sliding spool type and the bore containing the slide valve 87 is connected by a conduit 89 to branch conduits 90 leading to the fluid cylinders of the power swing jacks 10 for the disintegrating head mechanism 6. The bore containing the slide valve 88 is connected through a conduit 91 to branched conduits 92 leading to the fluid cylinders of the scroll elevating jacks 67. Also communicating with the conduit 91 is a conduit 93 connected by branched conduits 94 to the fluid cylinders of the tilting jacks 22 for the forward tiltable portion 19 of the conveyor frame. The conduit 91 is connected by a conduit 95 through a conventional relief valve 96 to the discharge conduit 86 so that in the event pressure in the conduit 91 becomes excessive the pressure may be automatically relieved. Whenever the valve 88 is positioned to supply fluid under pressure to the conduit 91 pressure fluid may flow to the tilt jack

cylinders 22 to elevate the tilttable portion 19 of the conveyor frame and concurrently pressure fluid may flow through branch conduits 92 to the elevating jack cylinders for the scroll housings. Thus due to the coordination of the jack cylinders 22 and 68, whenever the forward portion of the conveying means is elevated, the conveyor scrolls are tilted upwardly about their pivots relative to the conveyor frame. Conversely when the forward portion of the conveying means are lowered the conveyor scroll housings concurrently swing downwardly about their pivots.

The general mode of use of the floor clean-up mechanism will be clearly apparent from the description given. When the slide valve 88 is positioned to vent the elevating cylinders 68 for the scroll housings the latter may ride on the mine floor and as the floor clean-up mechanism is advanced over the floor, the scroll housings may swing freely upwardly and downwardly about their pivots thereby to enable the conveyor scrolls to follow an uneven floor or rolling bottom. As the floor clean-up mechanism is advanced over the floor the conveyor scrolls, which are driven by the conveyor chain, are rotated thereby causing the spiral vanes thereof to engage and move the loose mineral inwardly through the scroll chambers 64 to discharge toward the forward portion of the conveying means so that some of the loose mineral may be received by the conveying means and the remainder may pile up on the floor in front of the conveying means beneath the disintegrating head mechanism, in the manner fully disclosed in a copending application to John R. Sibley and Raymond J. Wacht, Serial No. 542,556, filed October 25, 1955, likewise owned by the assignee of the present invention. Thus as the disintegrating head mechanism operates to dislodge and disintegrate the mineral of a solid mine vein in the manner disclosed in the above mentioned copending application Serial No. 102,995, any loose mineral which may fall to the mine floor may be gathered by the conveyor scrolls and moved in a position to be received by the conveying means 14. During trammimg of the continuous miner about the mine the forward receiving portion of the conveying means 14 may be elevated above the mine floor by the power jacks 22 and as the forward portion 19 of the conveyor frame is tilted upwardly the scroll housings are concurrently swung upwardly about their pivots relative to the conveyor frame. Thus during trammimg of the miner the floor clean-up mechanism is maintained in an elevated out-of-the-way position beneath the disintegrating head mechanism. Vertical swinging movement of the scroll housings in the downward direction about their pivots is limited by the stop pins 77 engaging the ends of the slots 78 while upward swinging of the scroll housings is limited by the abutment plates 79 engaging the lugs 76. Thus positive stops are provided at the limits of swing in opposite directions. By confining the pivotal motion of the conveyor scrolls about parallel longitudinally extending horizontal axes at opposite sides of the front receiving portion of the conveying means the structure is simplified and made more durable, while provision for free tilting of the scroll housings as they ride over an uneven floor is present.

As a result of this invention an improved floor clean-up mechanism is provided whereby any loose mineral which may fall to the mine floor during the mining operation may be effectively and expeditiously cleaned up and loaded onto the conveying means of the mining machine with which the floor clean-up mechanism is associated. By the provision of the improved pivotal mountings for the conveyor scrolls the latter may readily follow the contour of an uneven floor or rolling bottom and may be readily swung into elevated position or lowered in an improved manner. The improved stop means limit tilt of the scroll housings in opposite directions while providing for free tilting of the housings as they ride over an uneven surface. The novel structural arrangement

of the scroll housings and supports and their pivotal mountings not only provides for compactness and efficiency but also provides for durability thereby rendering the clean-up mechanism well adapted for its intended purpose. By coordinating the tilt cylinders for the conveying means with the elevating cylinders for the scroll housings the conveyor scrolls are swung about their pivots whenever the conveying means is elevated. Other advantages of the invention will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a floor clean-up mechanism, a support movable over the floor of a mine, conveying means on said support and having a front receiving portion, scroll housings pivotally mounted at the opposite sides of said front receiving portion of said conveying means to tilt in vertical planes extending transversely of said conveying means and said support, conveyor scrolls journaled on said scroll housings and operating at the floor level, pivotal mounting means for said scroll housings for confining the same to tilting movement about horizontal axes extending longitudinally of said support along lines perpendicular to said transverse vertical planes, and extensible power devices projecting laterally from the sides of said conveying means with their longitudinal axes lying in a vertical plane parallel with the vertical planes of tilt of said scroll housings, said power devices being pivotally connected to said support and to said scroll housings with the pivots of the connections pivotally disposed in parallelism with the axes of tilt of said scroll housings.
2. In a floor clean-up mechanism, a support movable over the floor of a mine, scroll housings projecting laterally from the opposite sides of said support, means for pivotally mounting said scroll housings on said support to tilt in vertical planes extending transversely of said support about parallel horizontal axes extending longitudinally of said support along lines perpendicular to said transverse vertical planes, conveyor scrolls journaled on said scroll housings and operating at the floor level, and means for tilting said scroll housings upwardly about their pivotal axes, said pivotal mounting means confining the pivotal motion of said scroll housings to said transverse vertical planes in all tilted positions of said housings.
3. A floor clean-up mechanism as set forth in claim 2 wherein said tilting means for said scroll housings comprises extensible power devices projecting laterally from the sides of said support with their longitudinal axes lying in a common vertical plane disposed in parallelism with the transverse vertical planes of tilt of said scroll housings.
4. A floor clean-up mechanism as set forth in claim 2 wherein means is provided for limiting the range of tilt of said scroll housings in one direction relative to said support, said limiting means comprising stop pins on one part received in slots in another part with the ends of the slots limiting the movement of said pins in one direction.
5. In combination, conveying means having a tilttable forward portion, floor clean-up devices projecting laterally from the opposite sides of said tilttable forward portion and adapted to operate at the floor level, means for pivotally mounting said devices on said tilttable forward portion for tilting movement in upright planes relative to said tilttable forward portion, means for tilting said forward portion, and means coordinated with said tilting means for concurrently tilting said clean-up devices in

upright planes about their pivots relative to said tiltable forward portion concurrently with tilting of the latter.

6. A combination as set forth in claim 5 wherein said tilting means for said forward portion comprises fluid motors and said tilting means for said gathering devices comprises fluid motors and means for operatively connecting said last mentioned fluid motors in series with said first mentioned fluid motors.

7. A combination as set forth in claim 6 wherein but a single control valve is provided for effecting the supply of operating fluid concurrently to both sets of said fluid motors.

8. A floor clean-up mechanism comprising, in combination, a support movable over the floor of a mine, scroll housings projecting laterally from the sides of said support, conveyor scrolls journaled on said housings and operating at the floor level for gathering loose mineral on the floor, said scrolls inclined forwardly and inwardly and projecting freely at their inner ends beyond the inner ends of said housings, and projections secured to said housings and extending inwardly longitudinally thereof beneath said free ends of said scrolls for directing the mineral discharged from said scrolls in an inward direction.

9. A floor clean-up mechanism as set forth in claim 8 wherein said scroll housings have scroll receiving chambers provided with curved inner surfaces conforming to the curvature of the exteriors of said scrolls, and said longitudinal projections have curved upper surfaces providing continuations of curved surfaces of the lower portions of said scroll chambers.

10. In combination, a support movable over the floor of a mine, a scroll housing projecting laterally from said support and a conveyor scroll journaled on said scroll housing and operating at the floor level, means for pivotally mounting said scroll housing on said support to tilt in vertical planes extending transversely of said support and comprising a bracket secured to the adjacent side of said support, said bracket having spaced lateral lugs supporting pivot pins arranged in spaced apart axial alignment, said scroll housing having spaced perforated lugs pivotally engaging said pivot pins, said pivotal mounting means confining said scroll housing to tilting movement about a horizontal axis extending longitudinally of said support along a line perpendicular to said transverse vertical planes.

11. A floor clean-up mechanism as set forth in claim 10 wherein an extensible power device is pivotally mounted on said support and is arranged transversely of

said support with its longitudinal axis lying in a vertical plane extending transversely of said support and is operatively connected to the upper portion of said scroll housing, the pivotal axes of said power device and its pivotal connection with said scroll housing being permanently arranged in parallelism with the pivotal axis of said scroll housing.

12. A floor clean-up mechanism as set forth in claim 10 wherein stop means is provided for limiting vertical tilt of said scroll housing in either direction including a slotted vertical plate secured to the upper portion of said scroll housing and a stop pin movably connected to said support and engaged in the slot of said slotted plate, said pin and slotted plate limiting the tilt of said scroll housing in one direction while permitting limited free tilt of said scroll housing in the opposite direction.

13. A floor clean-up mechanism as set forth in claim 12 wherein said stop means also includes coacting abutment elements on said support and scroll housing for limiting the range of tilt of said scroll housing in the opposite direction.

14. A floor clean-up mechanism as set forth in claim 12 wherein said stop means includes an abutment surface on said support engageable by a surface on said vertical plate for limiting the tilt of said scroll housing in the opposite direction.

15. A floor clean-up mechanism as set forth in claim 3 wherein stop means is provided disposed in planes parallel with said common vertical plane for limiting tilting movement of said scroll housings in opposite directions.

16. A floor clean-up mechanism comprising a support, a scroll housing pivotally mounted at one side of said support to tilt in transverse vertical planes about a horizontal axis permanently extending longitudinally of said support along a line perpendicular to said transverse vertical planes, an extensible power device arranged with its longitudinal axis lying in a vertical plane parallel with said planes of tilt of said scroll housing, and stop means disposed in transverse vertical planes for limiting the range of tilt of said scroll housing in either direction.
